UNITED STATES PATENT OFFICE.

LEWIS CALVIN BULLOCK, JR., OF STATE COLLEGE, PENNSYLVANIA.

SHOESTRING-FASTENING DEVICE.

1,348,475.

Specification of Letters Patent.

Patented Aug. 3, 1920.

Application filed March 11, 1920. Serial No. 364,878.

To all whom it may concern:

Be it known that I, LEWIS C. BULLOCK, Jr., a citizen of the United States, residing at State College, in the county of Center 5 and State of Pennsylvania, have invented certain new and useful Improvements in Shoestring-Fastening Devices, of which the following is a specification.

One object of my invention is to provide 10 an improved device which can be secured to the tongue of a shoe and which will serve to hold the shoe strings in their proper position preventing them from accidentally becoming untied and at the same time will 15 hold the tongue of the shoe in its proper position preventing it from wrinkling or falling from its intended position.

Another object is to make the device of 20 my invention of a simple and durable construction, so that it can be easily attached to the tongue of the shoe and can be easily used with advantage for the purposes above mentioned.

These objects, and other advantageous 25 ends which will be described hereinafter, I attain in the following manner, reference being had to the accompanying drawings in which—

Figure 1 is a perspective view of a device 30 made in accordance with my invention,

Fig. 2 is a side elevation showing said device attached to the tongue of a shoe,

Figs. 3, 4 and 5 are fragmentary elevational views, partly in perspective, showing 35 how my invention can be employed to permit the tying of the lace string of a shoe so that when tied the string will not accidentally become unfastened and the tongue will be held in proper position relatively to the 40 upper of the shoe,

Fig. 6 is a view of similar character to Fig. 2 showing a slight modification in the device of my invention, and

Figs. 7 and 8 are views of similar character to Figs. 2 and 6 showing other modified forms of the device of my invention.

Referring to Figs. 1 to 5 inclusive my improved fastening device consists of a plate 9 which is preferably made of metal and 50 stamped or forged so as to produce integral sleeves 10 which may be forced through the tongue 11 of a shoe and afterward clenched or beaded at the outer ends 12 to secure the plate to the tongue as clearly shown in Fig. 2. The clenching sleeves 10 are spaced 55 apart so as to firmly hold the plate 9 to the

tongue and the plate 9 has a rib 13 projecting forwardly therefrom; said rib being positioned preferably centrally between said sleeves as clearly shown in Fig. 1. The top 60 edge of the rib 13 has a downwardly extending notch 14 therein which tapers inwardly from said top edge and said rib 13 immediately below said notch has a hole 15 extending therethrough; the edge 16 forming said hole being continuous as clearly shown in Figs. 1 and 2. The plate 9 is secured to the tongue 11 of the shoe immediately adjacent its top so that when said tongue is positioned as shown in Fig. 3, the 70 plate 9 and rib 13 will be located adjacent the top edge 17 of the shoe upper 18 with the hole 15 of the plate slightly above the top lacing holes 19 of the upper; the notch 14 being positioned above the hole 15 so 75 that the rib 13, which is made comparatively narrow, can project outwardly through the parting 20 of the front edges of the shoe upper 18.

After the tongue has been placed in said 80 position the end portions 21 and 22 of the shoe string or lace are projected in opposite directions through the hole 15, as shown in Fig. 3, after which a loop 23 is formed in the shoe lace by imparting a "first tie" 24 85 to the ends of the shoe lace and this loop is then reduced in size by pulling the end portions of the lace until the wrapped part 24 of the lace is forced down into the notch 14 and drawn taut as shown in Fig. 4; said 90 inwardly tapering part of the notch serving as guiding means to permit the wrapped portions 24 to be drawn tightly into said notch and so that the lace thus far tied will surround and bind the portion 25 of the 95 rib 13 between the inner end of the notch 14 and the hole 15. The usual looped bow 26 can then be formed and drawn taut so that its wrapping 27 will also be drawn down into the notch above the wrapped portion 100 24 and due, to the resilient characteristic of the material out of which a lace is usually made, the portion 27 of the bow will be firmly held within the notch as clearly shown in Fig. 5. It will also be noted that 105 the above tying of the parts will firmly anchor or hold the rib in position and since the rib is attached to the tongue through the medium of the plate 9 and clenching sleeves 10, it will be impossible for the 110 tongue to move downwardly out of position.

In Fig 6 I have shown a modification

which is similar to that described in Figs 1 to 5 inclusive with exception that the notch 14 has a restricted throat 14^a and a comparatively wide inner portion 14^b so that in drawing the portions of the lace into the notch they will first be compressed when passing through the restricted portion 14^a and after passing farther into the notch they can expand within the inner portion 14^b of the notch and will not readily move out of the notch in view of the comparatively narrow portion 14^a being located directly above the portion 14^b.

In Fig 7 I have illustrated another form 15 of the device of my invention including two holes 15^a and 15^b which are located at opposite sides of a notch 14^c and in this instance the device can be attached with either 20 of the holes 15^a or 15^b above the notch 14^c and the ends of the lace can be initially projected in opposite directions through the holes 15^a and 15^b and afterward tied and the tied portions forced within the notch 15^c.

The form of my invention shown in Fig. 25 8 is similar to that shown in Fig. 7 with the exception that the notch 14^a between the holes 15^a and 15^b has a restricted portion 14^a similar in use to the restricted portion 14^a described in connection with Fig. 6. In all 30 other respects the forms of my invention shown in Figs. 6, 7 and 8 are similar to that described in connection with Figs. 1 to 5 inclusive and I have therefore given corresponding parts similar reference numerals.

35 While I have described my invention as taking a particular form, it will be understood that the various parts of my invention may be changed without departing from the spirit thereof, and hence I do not limit myself to the precise construction set forth, 40 but consider that I am at liberty to make such changes and alterations as fairly come within the scope of the appended claims.

Having thus described my invention, what 45 I claim as new and desire to secure by Letters Patent is:—

1. A device of the character described including a plate adapted to be secured to the tongue of a shoe and having a rib forwardly 50 projecting therefrom whereby the rib can pass outwardly through the parting between the front edges of the shoe upper, said rib having a hole through which the end por-

tions of the shoe lace can be projected and a notch adjacent said hole whereby a portion 55 of the lace, wrapped to form a loop, can be pulled when the loop is shortened; substantially as described.

2. A device of the character described including a plate adapted to be secured to the tongue of a shoe and having a rib forwardly projecting therefrom whereby the rib can pass outwardly through the parting between the front edges of the shoe upper, said rib having a hole through which the end portions of the shoe lace can be projected and a notch adjacent said hole whereby a portion 60 of the lace, wrapped to form a loop, can be pulled when the loop is shortened, said notch being positioned above said hole; 70 substantially as described.

3. A device of the character described including a plate adapted to be secured to the tongue of a shoe and having a rib forwardly projecting therefrom whereby the rib can 75 pass outwardly through the parting between the front edges of the shoe upper, said rib having a hole through which the end portions of the shoe lace can be projected and a notch adjacent said hole whereby a portion 80 of the lace, wrapped to form a loop, can be pulled when the loop is shortened, said notch being positioned above said hole and projecting downwardly from the top edge of said rib; substantially as described. 85

4. A device of the character described including a plate adapted to be secured to the tongue of a shoe and having a rib forwardly projecting therefrom whereby the rib can pass outwardly through the parting between the front edges of the shoe upper, said rib having a hole through which the end portions of the shoe lace can be projected and a notch adjacent said hole whereby 90 a portion of the lace, wrapped to form a 95 loop, can be pulled when the loop is shortened, said notch having a restricted throat between its outer and inner ends; substantially as described.

In testimony whereof I have signed my 100 name to this specification in the presence of two subscribing witnesses.

LEWIS CALVIN BULLOCK, JR.
